UNITED STATES PATENT OFFICE

144,081

DESIGN FOR A ROTATIVE WINGED AIRCRAFT

Paul H. Stanley, Huntingdon Valley, Pa., assignor to Autogiro Company of America, Philadelphia, Pa., a corporation of Delaware

Application May 19, 1942, Serial No. 106,955

Term of patent 14 years

(Cl. D71—1)

To all whom it may concern:

Be it known that I, Paul H. Stanley, a citizen of the United States, residing at Huntingdon Valley, in the county of Montgomery and State of Pennsylvania, have invented a new, original, and ornamental Design for a Rotative Winged Aircraft, of which the following is a specification, reference being had to the accompanying drawings, forming a part of this application.

Figure 1 is a perspective view of a rotative winged aircraft of my design.

Figure 2 is a side elevational view of the rotative winged aircraft shown in Figure 1.

Figure 3 is a top plan view of the rotative winged aircraft shown in Figure 1.

I claim:

The ornamental design for a rotative winged aircraft, as shown.

PAUL H. STANLEY.
